APPARATUS FOR MAKING ICE

Willis B. Kirkpatrick, Scarsdale, N. Y.

Application January 21, 1948, Serial No. 3,463

11 Claims. (Cl. 62—106)

1

This invention relates to the manufacture of ice and it has for its object to provide a novel and improved apparatus for making ice cubes economically and in large volume.

Another object of the invention is to provide a simple and efficient machine for producing ice cubes of uniform size with flat square tops and in a form clear enough to be readily merchantable.

Another object is to provide a machine of the type specified which is capable of full automatic operation and is therefore especially adapted for use in hotels, restaurants, cafes, soda dispensaries and the like.

Another object is to provide a novel ice cube machine which freezes the cubes in individual compartments, thaws the ice cubes from the walls of said compartments, and automatically discharges them onto a delivery chute or conveyor, in the shortest possible time and with a minimum of maintenance and supervision.

Still another object is to provide an ice cube machine of the foregoing type having novel and improved details of construction and features of operation.

Various other objects and advantages will be apparent as the nature of the invention is more fully disclosed.

Ice cubes which are frozen in stationary trays, as in a conventional household refrigerator, are not commercially saleable because the tops of the cubes are always uneven and the cubes are also objectionably white or cloudy due to the absence of agitation while the water is freezing. Another objection to such cubes is that they contain occluded salts and other impurities, which can only be avoided by constantly removing and replenishing the core water during the freezing operation.

For these and other reasons, nearly all the ice cubes which the trade supplies in large quantities to hotels, restaurants, etc., are made by subdividing large cakes of ice produced in commercial ice plants. In practice, a cake of ice weighing usually three hundred pounds is placed in a machine having a series of saws which saw the cake into approximately two thousand cubes. This process entails considerable expense due to the waste of about thirty percent of the ice from the cuts made by the saws, the labor required to handle the cakes of ice and the snow or "saw-dust" produced by the saws, and the repairs to the machine consisting chiefly in the replacement of the saws when they become dull or cracked.

Another objection to the above-mentioned cutting machines is the poor quality of the ice cubes

2

which they produce. The cubes are not regular in size due to the tapering sides and irregular tops of the cakes of ice from which they are cut, and more particularly due to the gradual wearing of the edges of the saws. Furthermore, the cubes sawed from the center of the ice cake are usually opaque or cloudy due to the presence of suspended matter and impurities which collect in the center of the cake because of their lower freezing point and are finally trapped and solidified with whatever air is present to form what is known in the trade as the "core" in the ice cake.

My invention overcomes the foregoing disadvantages of the prior art by providing a machine which automatically freezes ice cubes of uniform size with the surfaces forming perfect cubes of crystal clear ice. In the embodiment disclosed herein for purposes of illustration, my machine comprises a rotatable cylinder or drum containing a multiplicity of open-ended ice cube compartments having bottom and side walls extending into and forming a part of the interior of the drum through which a refrigerant is circulated. The rotatable drum has an outer shell-like cover preferably composed of two semi-cylindrical walls which are hinged together along one longitudinal edge so that the cover is adapted to open or close upon the drum in a manner somewhat similar to the operation of a hinged "bracelet" or "clamshell bucket."

The drum, containing the open-ended ice cube compartments on its cylindrical surface, is adapted to rotate continuously while the machine is in use. At the start of the freezing operation the cover is closed upon the drum and locked thereon, in a manner hereinafter described, so that the cover rotates with the drum. When so closed upon the drum, the cover forms a flat top for the open ends of all the ice cube compartments and insures the formation of flat-topped ice cubes during the freezing operation.

The hinged cover of the machine contains a plurality of apertures or holes which permit water to pass into and out of the ice cube compartments as the drum and cover rotate as a unit during the freezing operation. In the embodiment illustrated herein, the cover contains one such hole for each ice cube compartment, and proper centering of said holes above the various compartments is assured by the locking means which secure the cover to the drum.

Means are provided for admitting water or other liquid to the ice cube compartments during the freezing operation. In the preferred embodiment of the invention, the outer surface of the

hinged cover has a plurality of longitudinal ribs containing "pockets" or scoops which trap water from a suitable supply source and direct it through the above-mentioned apertures into the ice cube compartments when tilted to the proper pouring angle by the rotation of the covered drum. The limited quantity of water thus admitted to each cube compartment is largely frozen in said compartments before the compartments assume a downwardly-tilted position due to the rotation of the covered drum, any unfrozen excess simply dripping out through the apertures and slopping over into a stationary tank beneath the drum.

The water supply referred to above may comprise a spray pipe which pours refrigerated water into the scoops on the cover during the freezing operation. Each successive charge of cold water admitted to the cube compartments builds up the ice therein, until the ice cubes are fully formed. At the conclusion of the freezing operation the temperature of the refrigerant circulating through the drum is raised sufficiently to thaw the ice cubes from the walls of the cube compartments, after which the cover is opened and brought to a stop with the open edge at the bottom of the machine to permit the rapid discharge of ice cubes by gravity as the drum continues to rotate.

Although the novel features which are characteristic of this invention are set forth more in detail in the claims appended hereto, the nature and scope of the invention may be better understood by referring to the following description, taken in connection with the accompanying drawings, forming a part thereof, in which certain specific embodiments have been set forth for purposes of illustration.

In the drawings:

Fig. 1 is a front elevation of an ice cube-making machine embodying the invention, with the discharge chute shown in section;

Fig. 2 is an enlarged transverse section through the machine of Fig. 1;

Fig. 3 is a longitudinal section through one of the files of ice cube compartments with the outer cover in closed position;

Fig. 4 is a perspective view of the feed pipe and tray for supplying liquid to the ice cube compartments;

Fig. 5 is an enlarged fragmentary view of the peripheral portion of the machine, corresponding with Fig. 2 but showing liquid trapped in the scoops which feed same to the ice cube compartments;

Fig. 6 is a front elevation of the machine proper, with parts of the operating mechanisms shown in section;

Fig. 7 is an end view of the machine shown in Fig. 6 but with the outer cover open to discharge the ice cubes;

Fig. 8 is a fragmentary view corresponding with Fig. 7 but with the cover closed; and

Fig. 9 is a front elevation corresponding with Fig. 6 but illustrating a modification of the invention.

In the following description certain specific terms are used for convenience in referring to the various details of the invention. These terms, however, are to be interpreted as broadly as the state of the art will permit.

The machine shown in the drawings comprises a rotatable drum or cylinder A (Fig. 2) and an outer shell or cover B (Figs. 1 and 2).

The rotatable drum A comprises a cylindrical

wall 1 having circular end plates 2 secured to a hollow shaft 3 which is journaled in bearings 4 carried by standards 5 and is adapted to be rotated by means of a pulley 6 (Figs. 1 and 6).

5 In the embodiment illustrated, the cylindrical wall 1 of drum A is integral with the end plates 2 thereof, the drum preferably being made of two semi-cylindrical metal castings welded together to form a fluid-tight unit.

A suitable refrigerant, either gaseous or liquid, is supplied to the interior of drum A through one end of the hollow shaft 3, entering the drum through openings 7 in the shaft adjacent one end plate 2 (Fig. 2) and then, after circulating throughout the interior of the drum, passing through similar openings 7 in shaft 3 adjacent the opposite end plate 2, and thence out through the far end of the shaft. It will be understood that the central portion of shaft 3 is solid to prevent the refrigerant from being short-circuited directly through the shaft.

The cylindrical wall 1 of drum A contains a plurality of spaced files of ice cube compartments 8 the bottom and side walls of which extend into and form a permanent part of the refrigerant-containing interior chamber of the drum, and the outer ends of which are open (Figs. 2, 3, 5 and 9). The side walls of the compartments 8 taper inwardly slightly toward the bottom walls thereof (Figs. 3 and 5) to facilitate the discharge of the ice cubes from said compartments at the conclusion of each freezing operation.

The outer shell or cover B of the machine comprises a separable cylinder composed of two semi-cylindrical walls 10 which are joined along one of their meeting edges by a longitudinal hinge 12. Thus, when the two semi-cylindrical halves 10 of cover B are forced apart they will swing open about their hinge 12 somewhat like a "clam-shell bucket," causing the ends of said cover diametrically opposite the hinge 12 to separate (Fig. 7) and permit the discharge of ice cubes from the cube compartments 8 of drum A, as hereinafter more fully described.

The two semi-cylindrical walls 10 of the cover B are preferably aluminum castings having a smooth interior lining 13 of hard rubber since I have found that such a rubber lining is easily separated from the tops of the ice cubes in compartments 8 when it is desired to discharge the ice cubes. The water or other liquid to be frozen in compartments 8 is admitted to said compartments through apertures here shown as rectangular holes 14 lined with metal ferrules (Figs. 2, 3 and 5) which extend through the walls 10 and linings 13, there being one such hole 14 allotted to each cube compartment 8. Each of these holes 14 is aligned with the center of one of the cube compartments 8 when the cover B is closed during the freezing operation, as will hereinafter more fully appear.

The outer convex surfaces of the two semi-cylindrical walls 10 of cover B are provided with longitudinal ribs 15 which are preferably cast integral with said walls and are positioned between each longitudinal file of holes 14, as shown in Figs. 1, 2 and 6. Each of these longitudinal ribs contains a series of spaced "pockets" or scoops 16 having their mouths positioned adjacent the various holes 14 leading to the cube compartments 8 so that liquid trapped in said scoops during the rotation of drum A and cover B, in a manner hereinafter described, will spill over into the holes 14 and thence into the respective cube

compartments 8 when tipped sufficiently by the rotary motion of the machine.

I shall now describe the means by which the cover B is locked upon the drum A so as to cause the cover to rotate with the drum in the proper relation to insure the continuous feeding of liquid to the cube compartments 8 during the freezing operation. Disposed about the periphery of each circular end plate 2 of rotatable drum A are a plurality of spaced recesses 18, as shown in Fig. 7, and these recesses are adapted to receive the similarly spaced rollers 19 which are mounted inside the end rims of cover B, as also shown in Fig. 7. Now, in the position shown in Fig. 7 the two semi-cylindrical walls 10 of cover B are spread apart on their hinge 12, and in order for the walls 10 of the cover to close upon the drum A it is necessary for the rollers 19 on the cover to enter the recesses 18 in the end plates 2 of the drum.

The mechanism for opening and closing the cover B about its hinge 12 is best shown in Figs. 6, 7 and 8. At each end of cover B I provide a bell crank consisting of a pair of levers 20 which are jointly fulcrumed at 21 to the reciprocating plunger 23 of a pneumatic or hydraulic motor 24 and have their other ends fulcrumed at 25 to the ends of the respective semi-cylindrical walls 10 of cover B adjacent the free ends of said walls 10. The motors 24 each contain two ports 26 and 27 for the admission of a fluid such as compressed air when it is desired to operate the motors to open or close the cover B. The mechanism for operating these motors automatically will be described later. For the present, with cover B shown in open position in Fig. 7, it may be said that in order to close said cover upon the drum A a fluid such as compressed air is admitted through port 27 of each of the two motors 24, thus forcing the plunger 23 upwardly (as viewed in Fig. 7) and operating the levers 20 to move the semi-cylindrical walls 10 of cover B to the closed position shown in Fig. 8. During this upward movement of plunger 23 the air in the upper part of motor cylinder 24 escapes to the atmosphere through a port 28 in the plunger, a similar port 29 being provided in the opposite end of the plunger for the escape of air whenever the plunger moves downwardly (as viewed in Figs. 7 and 8) to open the cover.

It will be understood that the drum A is rotating continuously during the above-mentioned cover closing operation, and, as soon as the drum rotates to a point where the recesses 18 in its end plates 2 register with the rollers 19 on the cover B, the said rollers 19 will enter the recesses 18 and the cover will close tightly about the cylindrical surface of the drum, causing the cover to rotate with the drum. During all the time that the cover B is rotating with the drum A it will be noted that the outer or free end of the plunger 23 of each fluid motor 24 is retracted, as shown in Fig. 8. This free end of each plunger 23 carries a roller 30 which rides in a stationary circular channel-shaped track 31 secured to the standard 5 at each end of the machine as best shown in Figs. 1, 6 and 7. These stationary tracks 31 are cut away at the bottom of the machine; that is, a segment is cut out of the bottom of each track 31, as shown in Figs. 7 and 8, so that the plunger 23 can descend and thereby open the cover B only when said cover B is in the position shown in Fig. 7 with the hinge 12 at the top and the separable edges of cover walls 10 (diametrically opposite the hinge 12) at the bot-

tom. If the fluid motors 24 should be energized to open the cover B at any other time (that is, while the rollers 30 of plungers 23 are riding in the tracks 31) the plungers will be unable to move and the cover B will remain closed until the motors 24 (which are carried by the cover and rotate therewith) arrive at the open spaces or segments at the bottom of tracks 31, at which time the plungers 23 will descend and the cover will open.

When the cover B opens in the manner described above, the free ends of plungers 23 carrying rollers 30 will strike against a stationary stop member or bracket 32 on the standards 5 of the machine, thus positively restraining the cover B from rotating with the drum A (which continues to rotate at all times during the operation of the machine). With the parts in this position, as shown in Fig. 7, the machine is ready to discharge ice cubes from the cube compartments 8 through the opening at the bottom of the cover B.

As previously stated, the longitudinal ribs 15 on the outer convex surface of cover B contain a series of spaced "pockets" or scoops 16 having their mouths positioned adjacent the various apertures or holes 14 leading to the ice cube compartments so that liquid trapped in said scoops 16 during the rotation of drum A and cover B will spill over into the holes 14 and thence into the respective cube compartments 8 when tipped sufficiently by the rotary motion of the machine. The liquid (usually water) supply means comprises an elongated spray pipe 34 mounted on a stationary plate or apron 35 preferably made of rubber which extends along the face of the cover B adjacent the bottom thereof. Since drum A and cover B rotate in a clockwise direction as viewed in Figs. 2 and 7, the pipe 34 and apron 35 may be mounted in about the "eight o'clock" position where the scoops 16 on the rotating cover B begin to assume an upright position. The pipe 34 contains a series of spaced slots 36 (Figs. 2 and 3) which direct a steady film of water over the plate 35 and into the scoops 16 on the cover B.

The excess water flowing over the plate 35 drops into a tank or trough 37 which is mounted beneath the machine and contains a refrigerant-circulating coil 38 for maintaining the water in trough 37 just above the freezing temperature. A pump 39 (Fig. 1) feeds the cold water from trough 37 to the spray pipe 34 continuously during the freezing operation. Figs. 2 and 5 show water trapped in certain of the scoops 16 on cover B just before the rotation of the drum and cover (in a clockwise direction in Figs. 2 and 5) has tilted such trapped water through the holes 14 into the cube compartments 8. As the drum and its cover rotate beyond the position shown in Figs. 2 and 5, the water will spill over into the cube compartments 8; and, since such water is already just above the freezing point, it will be largely frozen before the slowly rotating drum, which preferably makes only four or five revolutions per minute, tilts the respective cube compartments to a water draining position. However, any unfrozen water remaining in the various compartments will drain out through the holes 14 in the cover into the trough 37 when a downwardly tilted position is reached. As the covered drum continues to rotate, each successive charge of cold water admitted to the cube compartments 8 will build up increasing films of ice therein, until the ice cubes are fully formed each with perfectly flat sides and bottom, and also with a perfectly flat top due to

the smooth flat surface of the hard rubber lining 13 of cover B which limits the height of the ice built up in the cube compartments.

In describing the operation of the machine shown in Figs. 1 to 8, it will of course be understood that it is possible for an attendant to perform the various operations manually or by actuating individual electrical or pneumatic controls, if desired. However, since this machine is especially adapted for use in hotels, restaurants, etc., where full-automatic operation is desirable, I shall describe the entire sequence of operations as performed automatically under the control of any suitable electrical timing device. The time control mechanism itself will not be described, however, since it forms no part of the present invention.

When the machine shown in Figs. 1 to 8 is set in operation, the shaft 3 carrying drum A is rotated through the pulley 6, and said drum A continues to rotate at all times while the machine is in use. Likewise the refrigerant, either gaseous or liquid, flows through one end of the hollow shaft 3 and circulates through the interior of drum A in intimate contact with the bottom and side walls of the cube compartments 8 which form a part of the interior chamber of the drum, the refrigerant passing out through the opposite end of shaft 3 to the refrigerating apparatus (not shown). Throughout the freezing operation the refrigerant is maintained at a suitable low freezing temperature; but during the thawing operation, hereinafter described, the temperature of the refrigerant is raised to a point which quickly thaws the ice cubes from the walls of the cube compartments; that is, the cycle of the refrigerant is reversed as in conventional household refrigerated ice boxes during the thawing off period. At the start of operations refrigerant also circulates through the coil 38 in water trough 37, and continues so to circulate while the machine is in use.

At the start of operations the cube compartments 8 of drum A are empty and the cover B is closed upon the drum, the pneumatic motors 24 being held in the "cover closed" position shown in Figs. 6 and 8 by compressed air flowing from the air lines 41 (Fig. 6) through ports in packing glands 42 of shaft bearings 4, valve ports 43 of solenoids 44, and ports 27 of motors 24. Accordingly, the cover B is locked upon the drum A and rotates with said drum as previously described. The pump 39 (Fig. 1) is likewise set in operation, feeding water from the trough 37 to the spray pipe 34.

As the drum A and cover B rotate as a unit (in a clockwise direction in Fig. 2) the cold water issuing from spray pipe 34 is directed by the apron 35 into the scoops 16 which, when sufficiently tilted by the rotation of the drum, dump the water through the holes 14 into the cube compartments 8. Each successive charge of water admitted to compartments 8 in this manner builds up the ice in said cubes, the agitation of the water created both by the flow of the water and the movement of the drum or cylinder insuring the formation of crystal-clear cubes, until the ice cubes are fully formed, as previously described. The freezing time is determined in advance for each type and size of machine constructed in accordance with the invention, the freezing time for the machine shown in Figs. 1 to 8 being forty-five minutes when the internal temperature of the drum created by the refrigerant is 12° F.

At the conclusion of the predetermined freez-

ing period the automatic control mechanism (not shown) stops the pump 39 and thus shuts off the supply of water to the spray pipe 34. At the same time the temperature of the refrigerant flowing through the interior refrigerating chamber is raised to a thawing temperature by reversing the cycle of the refrigerant, thus thawing the ice cubes from the walls of the cube compartments 8, and likewise thawing the flat metal tops between the compartments 8 from the interior lining 13 of cover B to facilitate the opening of said cover. After a predetermined thawing period, which is set by the timing mechanism, the ice cubes are ready to be discharged.

The automatic control mechanism now establishes an electrical circuit through contact brushes 45 and rings 46 (Figs. 1 and 6) thereby actuating solenoids 44 in a direction to close their valve ports 43 and open their ports 47 (Fig. 6). As a result, compressed air from the air lines 41 and the ports in packing glands 42 of shaft bearings 4 now flows through valve ports 47 of solenoids 44 and ports 26 of fluid motors 24, moving the pistons and plungers 23 of said motors 24 in a downward direction as viewed in Fig. 8. That is, the cover will open when the motors 24 are in a nearly vertical position at the bottom of the machine so that the plungers 23 can descend into the open spaces between the ends of the stationary tracks 31. As previously explained, if the fluid motors 24 happen to be energized to open the cover B while the rollers 30 of plungers 23 are riding in the tracks 31, the plungers will not operate until their rollers 30 emerge from said tracks 31 at the bottom of the machine, at which time said plungers will descend, the bell crank levers 29 will open the cover B upon its hinge 12, and the free ends of plungers 23 carrying rollers 30 will strike against the stationary brackets 32 to restrain the cover B from rotating with the drum A.

The drum A continues to rotate, and, as each longitudinal file of cube compartments 8 arrives at the bottom of the machine, the ice cubes therein will fall by gravity upon an inclined delivery chute 49 which is mounted on the water trough 37 and is suitably perforated at 50 (Figs. 1 and 2) to permit water to drip through into said trough. After the lapse of sufficient time to discharge all the ice cubes, which will require no more than one or two revolutions of the drum A while the cover B is open, the cycle of operations is repeated.

Fig. 9 illustrates a modification of the invention in which the fluid motors 24 for opening and closing the cover B are actuated by the same fluid refrigerant (preferably gaseous) which is used for freezing and thawing the ice cubes, thus eliminating the necessity for a separate air compressor such as is required in the machine of Figs. 1 to 8. The fluid motors 24 of Fig. 9 are constructed as previously described except that their plungers 23 do not contain any escape ports (such as the air escape ports 28 and 29 of Figs. 7 and 8). Furthermore, some of the valve ports controlled by the solenoids 44 in Fig. 9 differ from the ports and connections in Figs. 1 to 8; hence those elements which are unchanged in Fig. 9 have been given the same reference numerals as in Figs. 1 to 8, while the new elements in Fig. 9 have been assigned new reference numerals in the drawing.

The gaseous refrigerant, which circulates under pressure through the hollow shaft 3 in Fig. 9, will likewise flow through an opening 52 in shaft 3 and the packing gland 42 at the left of Fig. 9

into the duct 53 leading to the solenoid valve at said left end of the machine; and refrigerant from the fluid motor 24 at the right of Fig. 9 may, under conditions hereinafter described, be discharged through duct 54 and right-hand packing gland 42 into an opening 55 in hollow shaft 3 and thus returned to the refrigerant-circulatory system. In Fig. 9 the cover B is closed upon the drum A, and at such time the fluid motors 24 are maintained in the "cover-closing" position (similar to Fig. 8) by refrigerant gas flowing from shaft 3 at the left of Fig. 9, through duct 53, solenoid valve port 43 and port 27 of left-hand fluid motor 24, as well as through pipe 56 and port 27 of the right-hand fluid motor 24.

Now, when the control mechanism actuates the parallel-connected solenoids 44 to open the cover B, the left-hand solenoid 44 closes its port 43 and opens its port 47. Thereupon, the refrigerant passes from duct 53 through said port 47 into the port 26 of left-hand fluid motor 24, as well as through pipe 57 and port 26 of the right-hand fluid motor 24 in Fig. 9. At the same time, the operation of the right-hand solenoid opens its port 58 so that the refrigerant gas expelled by the outwardly moving pistons of both fluid motors 24 may be discharged through said port 58 and through duct 54 and shaft opening 55 to the interior of hollow shaft 3 which returns the gas to the circulatory system. In all other respects the machine of Fig. 9 operates in the manner previously described in connection with Figs. 1 to 8.

Although certain specific embodiments have been shown and described herein for purposes of illustration, it will be evident to those skilled in the art that the invention is capable of various modifications and adaptations within the scope of the appended claims.

The invention claimed is:

1. An ice making machine comprising a rotatable carrier having a plurality of open-ended ice cube compartments with bottom and side walls extending into the interior thereof and forming a chamber for the circulation of a refrigerant about said compartments, means for rotating said carrier, a cover for said carrier comprising separable walls adapted when closed to surround said carrier and close the ends of said cube compartments, means for opening and closing said cover, cooperating locking means on said carrier and cover securing same together to rotate in unison when said cover is closed, means to prevent opening of said cover except in position to discharge the contents of said ice cube compartments downwardly by gravity, said cover having apertures for admitting liquid to said cube compartments, and means for supplying liquid to said apertures during rotation of said carrier and cover.

2. An ice making machine comprising a rotatable carrier having a plurality of open-ended ice cube compartments with bottom and side walls extending into the interior thereof and forming a chamber for the circulation of a refrigerant about said compartments, means for rotating said carrier, a cover for said carrier comprising separable walls adapted when closed to surround said carrier and close the ends of said cube compartments, means for opening and closing said cover, cooperating locking means on said carrier and cover securing same together to rotate in unison when said cover is closed, means to prevent opening of said cover except in position to discharge the contents of said ice cube compartments downwardly by gravity, said cover having apertures leading to said cube compartments for the admis-

sion of liquid thereto, scoops for the reception of liquid on said cover adjacent said apertures for tilting said liquid into said apertures during the rotation of said carrier and cover, and means for supplying liquid to the scoops on said cover.

3. An ice making machine comprising a rotatable carrier having a plurality of open-ended ice cube compartments with bottom and side walls extending into the interior thereof and forming a chamber for the circulation of a refrigerant about said compartments, means for rotating said carrier, a cover for said carrier comprising a pair of hinged walls surrounding said carrier and closing the ends of said cube compartments

15 when said cover is closed, means for opening and closing said cover upon its hinge, cooperating locking means on said carrier and cover securing same together to rotate in unison when said cover is closed, means to prevent opening of said cover except when inverted to discharge ice cubes downwardly by gravity, said cover having apertures leading to said cube compartments for the admission of liquid thereto, and means for supplying liquid to said apertures during rotation of said carrier and cover.

4. An ice making machine comprising a rotatable carrier having a plurality of open-ended ice cube compartments with bottom and side walls extending into the interior thereof and forming a chamber for the circulation of a refrigerant about said compartments, means for rotating said carrier, a cover for said carrier comprising a pair of hinged walls surrounding said carrier and closing the ends of said cube compartments when

30 said cover is closed, means for opening and closing said cover upon its hinge, cooperating locking means on said carrier and cover securing same together to rotate in unison when said cover is closed, means to prevent opening of said cover except when inverted to discharge ice cubes downwardly by gravity, said cover having apertures aligned with said cube compartments for the admission of liquid on said cover adjacent said apertures for tilting said liquid into said apertures during the rotation of said carrier and cover, and means for supplying liquid to the scoops on said cover.

5. An ice making machine comprising a rotatable carrier having a plurality of open-ended ice cube compartments with bottom and side walls extending into the interior thereof and forming a chamber for the circulation of a refrigerant about said compartments, means for rotating said carrier, a cover for said carrier comprising a pair of hinged walls surrounding said carrier and closing the ends of said cube compartments when

35 said cover is closed, means including motor elements on the ends of said cover having plungers movable outwardly and inwardly to open and close said cover upon its hinge, cooperating locking means on said carrier and cover securing same together to rotate in unison when said cover is closed, means cooperating with the

40 plungers of said motor elements to prevent outward movement of said plungers except with said cover inverted to discharge ice cubes downwardly by gravity, said cover having apertures aligned with said cube compartments for the admission of liquid thereto, and means for supplying liquid to said apertures during rotation of said carrier and cover.

6. An ice making machine comprising a rotatable carrier having a plurality of open-ended ice cube compartments with bottom and side

11

walls extending into the interior thereof and forming a chamber for the circulation of a refrigerant about said compartments, means for rotating said carrier, a cover for said carrier comprising a pair of hinged walls surrounding said carrier and closing the ends of said cube compartments when said cover is closed, means including motor elements on the ends of said cover having plungers movable outwardly and inwardly to open and close said cover upon its hinge, cooperating locking means on said carrier and cover securing same together to rotate in unison when said cover is closed, means cooperating with the plungers of said motor elements to prevent outward movement of said plungers except with said cover inverted to discharge ice cubes downwardly by gravity, said cover having apertures aligned with said cube compartments for the admission of liquid thereto, scoops for the reception of liquid on said cover adjacent said apertures for tilting said liquid into said apertures during the rotation of said carrier and cover, and means for supplying liquid to the scoops on said cover.

7. An ice making machine comprising a rotatable cylindrical drum having a plurality of open-ended ice cube compartments with bottom and side walls extending into the interior of said drum and forming therewith a chamber for the circulation of a refrigerant about said compartments, means for rotating said drum, a cover for said drum comprising a pair of semi-cylindrical walls hinged together along one longitudinal edge and completely surrounding said drum and closing the ends of said cube compartments when said cover is closed, means including motor elements on the ends of said cover having plungers movable outwardly and inwardly to open and close said cover upon its hinge, cooperating locking means on said drum and cover securing same together to rotate in unison when said cover is closed, means cooperating with the plungers of said motor elements to prevent outward movement of said plungers except with said cover inverted to discharge ice cubes downwardly by gravity, said cover having apertures aligned with said cube compartments for the admission of liquid thereto, scoops for the reception of liquid on said cover adjacent said apertures for tilting said liquid into said apertures during the rotation of said drum and cover, and means for supplying liquid to the scoops on said cover.

8. An ice making machine comprising a rotatable cylindrical drum having a plurality of open-ended ice cube compartments with bottom and side walls extending into the interior of said drum and forming therewith a chamber for the circulation of a refrigerant about said compartments, means for rotating said drum, a cover for said drum comprising a pair of semi-cylindrical walls hinged together along one longitudinal edge and completely surrounding said drum and closing the ends of said cube compartments when said cover is closed, means including motor elements on the ends of said cover having plungers movable outwardly and inwardly to open and close said cover upon its hinge, cooperating locking means on said drum and cover securing same together to rotate in unison when said cover is closed, means cooperating with the plungers of said motor elements to prevent outward movement of said plungers except with said cover inverted to discharge ice cubes downwardly by gravity, said cover having apertures aligned with said cube compartments for the admission of liquid thereto, scoops for the reception of liquid on

12

said cover adjacent said apertures for tilting said liquid into said apertures during the rotation of said drum and cover, and means including a spray pipe extending longitudinally of said machine for supplying liquid to the scoops on said cover.

9. An ice making machine comprising a rotatable cylindrical drum having a plurality of open-ended ice cube compartments with bottom and side walls extending into the interior of said drum and forming therewith a chamber for the circulation of a refrigerant about said compartments, means for rotating said drum, a cover for said drum comprising a pair of semi-cylindrical walls hinged together along one longitudinal edge and completely surrounding said drum and closing the ends of said tube compartments when said cover is closed, means including motor elements on the ends of said cover having plungers movable outwardly and inwardly to open and close said cover upon its hinge, cooperating locking means on said drum and cover securing same together to rotate in unison when said cover is closed, stationary circular tracks on said machine adjacent the ends of said cover with an opening in said tracks at the bottom of the machine, rollers on the plungers of said motor elements riding in said tracks during the rotation of said cover to prevent outward movement of said plungers except through the openings in said tracks at the bottom of the machine, said cover having apertures aligned with said cube compartments for the admission of liquid thereto, scoops for the reception of liquid on said cover adjacent said apertures for tilting said liquid into said apertures during the rotation of said drum and cover, and means including a spray pipe extending longitudinally of said machine for supplying liquid to the scoops on said cover.

10. An ice making machine comprising a rotatable cylindrical drum having a plurality of open-ended ice cube compartments with bottom and side walls extending into the interior of said drum and forming therewith a chamber for the circulation of a refrigerant about said compartments, means for rotating said drum, a cover for said drum comprising a pair of semi-cylindrical walls hinged together along one longitudinal edge and completely surrounding said drum and closing the ends of said cube compartments when said cover is closed, means including motor elements on the ends of said cover having reciprocating plungers movable outwardly and inwardly to open and close said cover upon its hinge, cooperating locking means on said drum and cover securing same together to rotate in unison when said cover is closed, stationary circular tracks on said machine adjacent the ends of said cover with an opening in said tracks at the bottom of the machine, rollers on the plungers of said motor elements riding in said tracks during the rotation of said cover to prevent outward movement of said plungers except through the openings in said tracks at the bottom of the machine, said cover having apertures aligned with said cube compartments for the admission of liquid thereto, scoops for the reception of liquid on said cover adjacent said apertures for tilting said liquid into said apertures during the rotation of said drum and cover, a trough for refrigerated liquid beneath said drum and cover in position to receive excess liquid dripping from the latter, and means including a spray pipe extending longitudinally of said machine for supplying liquid from said trough to the liquid receiving scoops on said cover.

13

11. An ice making machine comprising a rotatable cylindrical drum having a plurality of open-ended ice cube compartments with bottom and side walls extending into the interior of said drum and forming therewith a chamber for the circulation of a refrigerant about said compartments, means for rotating said drum, a cover for said drum comprising a pair of semi-cylindrical walls hinged together along one longitudinal edge and completely encircling said drum and closing the ends of said cube compartments when said cover is closed, means including motor elements on the ends of said cover having reciprocating plungers movable outwardly and inwardly to open and close said cover upon its hinge, cooperating locking means on said drum and cover securing same together to rotate in unison when said cover is closed, stationary circular tracks on said machine adjacent the ends of said cover with an opening in said tracks at the bottom of the machine, rollers on the plungers of said motor elements riding in said tracks during the rotation of said cover to prevent outward movement of said plungers except through the openings in said tracks at the bottom of the machine, said cover

having apertures aligned with said cube compartments for the admission of liquid thereto, scoops for the reception of liquid on said cover adjacent said apertures for tilting said liquid into said apertures during the rotation of said drum and cover, a trough for refrigerated liquid beneath said drum and cover in position to receive excess liquid dripping from the latter, means including a spray pipe extending longitudinally of said machine for supplying liquid from said trough to the liquid-receiving scoops on said cover, and means for receiving ice cubes discharged by gravity through the opening in said cover at the bottom of the machine.
